UNITED STATES PATENT OFFICE

CHAMPE S. ANDREWS, OF NORTH CHATTANOOGA, TENNESSEE

FOLDED BOX

Application filed December 26, 1930. Serial No. 504,693.

This invention relates to folded boxes of the type comprising a body portion and a hinged cover portion formed from a single blank.

The invention consists in providing a one piece box wherein the lines of the sides of the box both interiorly and exteriorly are smooth; whereby great strength and rigidity is secured without the sacrifice of appearance; and further consists in a novel method of assembling and securing the parts from a single blank in their finished or set up position.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, and the manner in which it may be carried out may be better understood by referring to the following description taken in connection with the accompanying drawings forming a part thereof, in which

Fig. 1 is a plan view of a blank constructed in accordance with the present invention;

Fig. 2 is a perspective view of the box in partly set-up condition;

Fig. 3 is a perspective view of the set-up box with the cover open;

Fig. 4 is a perspective view of the set-up box with the cover closed;

Fig. 5 is a section taken in part on the line 5—5 of Fig. 3 but with the cover closed;

Fig. 6 is a broken perspective view of the box showing the arcuate tab;

Fig. 7 is a broken plan view of a blank showing a modified form of tab;

Fig. 8 is a broken perspective view of a portion of the box formed from the blank of Fig. 7 in partly set-up position; and

Fig. 9 is a broken perspective view of the same box in completely set-up position but with the cover open.

Like reference characters denote like parts in the several figures of the drawings.

In the following description and in the claims parts will be identified by specific

names for convenience, but they are intended to be as generic in their application to similar parts as the art will permit.

Referring more particularly to the drawings the box is shown as formed with a pair 55 of sections 10 and 11 which for convenience will be termed the "body member" and "cover member" respectively. Said members are joined by a connecting or back member 12. The blank is scored as at 13 to permit the 60 back member to be folded into upstanding position with respect to body members 10 and is scored as at 14 to provide a hinge for the cover member.

The blank is scored lengthwise to provide 65 outer side walls 15 and 16 for the body member 10 and the cover member 11 respectively and is scored transversely to provide front outer walls 17 and 18 respectively, the scoring of the body and cover being offset to permit 70 the body to seat within the cover of the completed box. Walls 15 and 16 have side flaps or inner walls 19 and 20 attached thereto, adapted to be bent about scores 21 and 22 respectively into engagement with the inner 75 surface of said outer walls whereby walls of double thickness are obtained. Front walls 17 and 18 have flaps 23 and 24 respectively secured thereto for a similar purpose. The walls 15 and 16 may also be provided with 80 tabs 25 and 26 respectively which are adapted to be bent into engagement with the inner surface of outer front walls 17 and 18 respectively and to be secured between same and the corresponding flaps when they are 85 bent into overlapping relationship.

Back member 12 is provided with tabs 27 which may be rectangular or arcuate or any other desired shape. Walls 15 are cut out or recessed to receive said tabs.

In assembling the blank, adhesive may first be applied to side flaps 19 and 20 and front flaps 23 and 24. The adhesive may be omitted from the portion of flaps 19 with which tabs 27 will contact. Flaps 19 and 20 are then bent over and secured to walls 15 and 16 and form the inner walls of the sides of the box. Walls 15 and 16 and front walls 17 and 18 are then bent upwardly at right angles to body 10 and cover 11 respectively and tabs 25 and 26 are 100

secured between front walls 17 and 18 and their corresponding flaps or inner walls 23 and 24, and permanently maintain the box in set-up position. Thereafter, adhesive is applied to the tabs 27 and the box is then in condition illustrated in Fig. 2.

The set-up is completed by bending member 12 about score 13 so that tabs 27 extend on the outside of the double side walls. Said tabs are then pressed inwardly into the cut out portion of said walls and into engagement with inner wall 19 to which they permanently adhere.

In this position the tabs 27 are coextensive with the corresponding recesses in the outer walls and lie flush with the outer surfaces of said walls, and are either rectangular, arcuate or other shape. After the tab is secured in this position, pressure may be applied to the outer surface of the tab to hold it in engagement with the outer surface of the inner wall or flap 19 of the side wall while the adhesive material is hardening or setting. The box is then in the condition shown in Fig. 3.

Thereafter, the cover 11 is bent about score 14 to close the box, thereby causing the side to press against tabs 27 and maintain said tabs in position and thereby eliminate any tendency of the tabs to become loose or to spring outwardly before the adhesive material is firmly set. It is to be understood that the boxes may be stacked and pressure applied to the entire stack for this purpose.

The side 15 may have a straight edge 29 contacting with a similar edge 28 on tab 27. If desired, however, these edges may take the arcuate form illustrated in Fig. 6 in which the various parts are identical with Figs. 1-5 with the exception of tab 30 which is provided with an arcuate edge 31, seating in a complementary recess in side member 15. It will be noted that in this form the arcuate edge is concentric with the hinge crease 14 and accordingly presents a neat pleasing appearance in addition to avoiding any corners or edges which could catch on the side 16 of the cover when the latter is closed.

In Figs. 7-9 a modification is shown in which sides 15 are provided with extensions 32 which are adapted to extend upwardly a slight distance from the bottom 10 when the box is in closed position and to thereby avoid any opening between the bottom and the side member. Back 12 is provided with a tab 33 which is adapted to seat in the recess 34 formed in side member 15. Said member 33 is preferably elongated in order to provide a greater surface for the adhesive material whereby the strength of the box is increased. The various other features of the box are identical with those illustrated in Figs. 1-5 and are given similar reference numerals.

It will be noted in the above described box that all of the tabs by which the box is held in set-up position are either concealed or lie

flush with the side walls of the box whereby they do not detract from the appearance of the box and from a mechanical standpoint they are sufficiently protected to avoid possibility of accidentally catching on other objects. The double thickness of the sides and front walls increases the strength of the box and permits the same to be formed from a blank of thinner material than would otherwise be required.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

What is claimed is:

1. A folded box formed from a one piece blank comprising a body section, and a cover section, and a back section joining said body and cover sections, said body and cover sections having side and front walls, tabs integral with said back section and adapted to engage said side walls to secure the back in set-up position, said side walls being recessed to receive said tabs and said tabs being seated in said recesses whereby they extend flush with the surface of said sides.

2. A box according to claim 1 wherein the side and front walls of the body section are of double thickness and the back section is of single thickness.

3. A box according to claim 1 in which the side and front walls are of double thickness and are permanently secured in set-up position by tabs attached to one of said walls and extending between the layers of the other of said walls.

4. A box according to claim 1 in which the body section has side walls of double thickness formed by bending the blank upon itself, the outer layer of the side wall having recesses formed therein complementary to said back tabs, said tabs being bent into said recesses and extending flush with the outer surface of the box.

5. A folded box formed from a one piece blank comprising a body member and a cover member joined by an intermediate back member, said body and cover members having side walls formed of two layers permanently secured together, said back member being held in set-up position by tabs located on the outside of said side walls and permanently secured to the inner layer of said walls, the outer layer of said walls being recessed to receive said tabs and permit the same to lie flush with the outer surface of the box.

6. A set-up box comprising a body member and an integral cover, said body member having side walls formed of two layers of material permanently secured together and a back member integral with said walls, said

- back member having tabs engaging the exposed surfaces of the inner layer and permanently secured thereto, said tabs being co-extensive with the outside of said box.
- 5 7. In a set-up box comprising a body member and an integral cover, said body member including, a plurality of walls formed of two layers of material permanently secured together, and a single-ply back wall, tabs secured to said back wall and in engagement with other of said walls for holding said box in set-up position, said other walls being recessed to receive said tabs whereby said tabs lie flush with the surface of said walls.
- 10 8. A set-up box comprising a body member and an integral cover, said body member having a plurality of upstanding multi-ply walls, an integral single-ply back wall connecting said cover and body portion, tabs secured to said back wall and engaging others of said walls for holding the box in set-up position, said other walls being recessed to receive said tabs and permit said tabs to lie flush with the surface of said walls.
- 15 9. A set-up box including a body portion and a back portion each having a plurality of upstanding walls, an integral back wall joining said body and cover portions, tabs secured to said back wall and engaging others of said walls for holding the box in set-up position, said other walls being recessed on the outside immediately adjacent the back to receive said tabs and to permit said tabs to lie flush with the outer surfaces of said walls.
- 20 10. A blank of box board comprising a body section and a cover section joined by an integral back section, side and end walls formed opposite said body section and cover section and flaps formed adjacent each of said side walls and end walls and scored to be bent back into engagement therewith, outwardly extending tabs formed on said back section, the side walls attached to said body section having a recess formed therein complementary to said tabs and adapted to receive the same when the box is in set-up position.
- 25 11. A blank of box board comprising a body section and a back section separated by suitable scores and double side walls formed on said body section, said side walls comprising a pair of sections which are scored for bending back upon themselves, tabs secured to the back section and a recess formed on the side sections nearest the back section, said recess being complementary to said tabs and adapted to receive the same when the box is in set-up position.
- 30 12. A box according to claim 1 in which said tabs have an arcuate edge concentric with the hinge of said cover section and seated in a complementary recess in said side walls.
- 35 13. A box according to claim 1 in which the tabs seat in a recess formed in the side walls of said box, which extends from the top of said side walls a part only of the distance to the bottom of said side walls whereby the entire lower edge of said side walls is made continuous with said bottom.
- 40 14. A set-up box comprising a body member and an integral cover, said body member having side walls formed of at least two layers of material permanently secured together, and a back member integral with said walls, said back member having tabs, the outer layers of said walls being recessed adjacent said back member to receive said tabs, said tabs being permanently secured in the recess of said walls and flush with the outside of the box.
- 45 15. A set-up box comprising a body member having side walls formed of at least two layers of material permanently secured together, and a back member integral with said walls, said back member having tabs, the outer layers of said walls being recessed adjacent said back member to receive said tabs, said tabs being permanently secured in the recess of said walls and flush with the outside of the box.
- 50 16. A box formed from sheet material comprising side walls and a bottom wall, one of said side walls comprising a main portion and an integral downfolded flap portion secured to said main portion to provide a double ply wall, said side wall being recessed at an outside end thereof, the adjacent side wall having a tab at one end thereof, said tab being permanently secured in the recess of said double ply wall and flush with the outside surface of said box.
- 55 17. A box formed from sheet material comprising side walls and a bottom wall, certain of said side walls comprising a main portion and an integral downfolded flap portion permanently secured to said main portion to provide double ply walls, said side walls being recessed at an outside end thereof, adjacent side walls having tabs at the ends thereof, said tabs being permanently secured in the recesses of said double ply walls and flush with the outside of said box.
- 60 In testimony whereof I have hereunto set my hand.
